FIG. 2

FIG. 1

FIG. 3

FIG. 4

FIG. 1 is a front elevational view of a hanger rod for a poultry cage support beam or similar article, showing my new design;

FIG. 2 is a side elevational view, the opposite side being substantially a mirror image thereof;

FIG. 3 is a rear elevational view; and

FIG. 4 is a fragmentary perspective view of the lower portion thereof, the fragment of beam shown in dotted lines being for illustrative purposes only.

A portion of the rod has been broken away and omitted in FIGS. 1, 2 and 3 to indeterminate length.

I claim:

The ornamental design for hanger rod for a poultry cage support beam or similar article, as shown and described.
